UNITED STATES PATENT OFFICE

ALBERT FALK, OF NEW YORK, N. Y., ASSIGNOR TO FALK TOBACCO COMPANY, OF NEW YORK, N. Y.

DESIGN FOR A LABEL-BLANK.

45,744.

Specification for Design.

Patented May 12, 1914.

Application filed March 9, 1914. Serial No. 823,588. Term of patent 7 years.

To all whom it may concern:

Be it known that I, ALBERT FALK, a citizen of the United States, residing at New York city, in the county of New York and State of New York, have invented a certain new, original, and ornamental Design for a Label-Blank, of which the following is a specification, reference being had to the accompanying drawing, forming a part thereof.

The figure is a plan view of a label blank showing my new and ornamental design.

I claim:

The ornamental design for a label blank, as shown.

ALBERT FALK.

Witnesses:

GROVER C. SNIFFEN,
E. M. CONNORS.
